(Cl. D87—3)

Fig.1

Fig.3

Fig. 2

Fig. 1 is a plan view of a portion of embossed plastic sheet material showing my new design on a reduced scale, a unit being enclosed within the dot-dash lines;

Fig. 2 is an enlarged view of the portion of Fig. 1 within the broken and dot-dash lines of that figure; and

Fig. 3 is an enlarged diagrammatic transverse sectional view through the material, the view being taken substantially on the section indicating line 3—3 of Fig. 2.

I claim:

The ornamental design for an embossed plastic sheet material, substantially as shown.
